FIG. 1.

FIG. 2.

FIG. 3.

R. Levens.
Inventor

By *Geo. P. Kimmel*,
Attorney

UNITED STATES PATENT OFFICE.

RICHARD LEVENS, OF PHILADELPHIA, PENNSYLVANIA.

ASBESTOS-SHEET CONNECTOR.

1,244,870.

Specification of Letters Patent. Patented Oct. 30, 1912.

Application filed December 5, 1916. Serial No. 135,167.

To all whom it may concern:

Be it known that I, RICHARD LEVENS, a citizen of the United States, residing at Philadelphia, in the county of Philadelphia 5 and State of Pennsylvania, have invented certain new and useful Improvements in Asbestos-Sheet Connectors, of which the following is a specification.

The present invention relates to fire-proof building structures, asbestos and otherwise and has particular reference to new and useful improvements in structural unit connectors.

An object of my invention is to provide a connector for asbestos sheets or the like used in building fire-proof buildings.

Another object of my invention is to provide a connector for asbestos sheets, metal sheets and the like which is strong and durable, cheap to manufacture and effective in use, the device being capable of quick and easy insertion in a building wall or the like during course of construction whereby to connect the adjoining edges of asbestos sheets or metal sheets to form the wall.

A further object of my invention is to provide a connector of the class described having a construction permitting expansion and contraction of the adjoining sheets, the 30 device also forming the vertical beams of the building.

A still further object of my invention is to provide a connector of the class described which not only securely connects adjoining sheet sections but also prevents ingress of dust, moisture, or the like.

Other objects and advantages to be derived from the use of my improved sheet connector for building structures will appear 40 from the following detailed description and the claims, taken with an inspection of the accompanying drawing, in which:

Figure 1 is a fragmental transverse sectional view of a sheet connector embodying the improvements of my invention;

Fig. 2 is an enlarged fragmental vertical sectional view of the same;

Fig. 3 is a similar view of the modified form of the invention; and

Fig. 4 is a fragmental sectional view of a modified form of the invention.

Referring more particularly to the drawing, wherein similar characters of reference designate like and corresponding parts throughout the various views, *a* and *b* designate in their entireties, the connector portions

of my invention. In view of the fact that the connector *a* is identical in construction with the connector *b* I shall describe but one of the same, reference being had to the connector *a*.

Referring specifically to the connector *a* the same is formed from a strip of metal 1 bent upon itself intermediate its side margins as at 2 and 3, a space 4 being provided between the main portion of the strip and the bent portions thereof for expansion and contraction purposes as will hereinafter appear.

The portions formed by bending the strips are in turn bent to form longitudinal walls 5 and 6 in slight spaced relation, the metal being again bent as at 7 to form longitudinal flanges 8 and 9. The free margins of the flanges are folded as at 10 to strengthen the same. It will be seen from an inspection of Fig. 1 that by bending the metal as shown a pair of elongated pockets 12 and 13 are provided in which the asbestos or metal sheets 14 and 15 may be inserted. The structure described in the foregoing would be used in some instances where a single wall construction is employed, but the general practice is to provide a double wall construction, and, of course, necessarily two of the connectors, as shown.

To properly associate the connectors *a* and *b*, I provide a plurality of transverse strips 15' having their free ends inserted between the walls 5 and 6, the extremities of said strips being bent to form tongues 16 for engagement in the expansion chamber 4. Any suitable means may be provided for retaining the tongues 16 in said chamber, such as soldering or the like.

A longitudinal stringer or beam 17 is shown in Figs. 1 and 2, said beam being wooden. When a wooden beam is employed as shown a pair of wood screws 18 and 19 are inserted through openings 20 formed in the connectors *a* and *b*, said wood screws 100 engaging the beam 17.

When a double wall construction is employed an inner wall is provided consisting of the plates or sheets 21 and 22 attached to the connector beam in a manner similar to 105 the sheets 14 and 15 hereinbefore referred to.

In some instances it may be desired to employ an entirely metallic superstructure for a building and in this instance the beam 17 would be substituted by a channel-iron 24 110 best shown in the modified form of my invention illustrated in Fig. 3.

The flanges 25 of the channel iron are provided with threaded openings in which the machine screws 26 are engaged, said machine screws passing through the connectors 5 *a* and *b* similarly to the wood screws 18 and 19 hereinbefore referred to. The construction of the connectors is identical in this form of my invention to the form shown in Figs. 1 and 2.

10 When the superstructure has been finished and the asbestos or metal plates inserted into position, the space between the same is usually filled with concrete. In this manner a solid and durable building structure is 15 afforded which is absolutely fire-proof and moisture-proof.

In Fig. 4 I have shown a modified form of my invention particularly adapted for use at the corners of buildings. The connector 20 in this instance includes a body *B* bent intermediate its ends as indicated at 28 to form a right-angular strip, the free margins thereof being formed with the plate receiving channels 29 and 30 similar to the channels hereinbefore referred to. The wall plates are designated 31 and 32 and are receivable in said channels. In a double wall construction two of the angular connectors 25 may be employed. It is not thought necessary to show the inner connector in view of the obvious manner in which the same would be arranged.

It will thus be seen that in constructing a building embodying the connectors and 35 plates as shown space is afforded for gas and electric conduits or for heating purposes or the like. The connecting members when made of stout metal not only serve as vertical I-beams similar to those in a metallic 40 building structure but also serve to connect the various sections of the wall. It will also be noted that the connector as formed permits connection of the plates thereto and also affords an expansion and contraction 45 joint variable under temperatures, yet at all times forming an intimate connection with the plates inserted thereinto, thereby effectively excluding moisture from a building.

From the above description taken in connection with the accompanying drawing, it 50 is thought that a clear and comprehensive

understanding of the construction, operation and advantages of my invention may be had, and while I have shown and described the device as embodying a specific structure, I 55 desire that it be understood that such changes may be made in said structure as do not depart from the spirit and scope of the invention as claimed.

Having thus fully described my invention, 60 what I claim as new and desire to secure by Letters Patent, is:

1. A device as specified including a pair of sections, each section being formed of a single sheet metal strip bent to form a pair 65 of oppositely disposed channels adapted to springingly engage objects to be connected, means for connecting said sections in spaced relation, and the extremities of the inner channel walls of each section being bent 70 back upon said walls to form a marginal enlargement to allow for expansion and contraction of the objects engaged, and to reinforce the edges of said walls.

2. A device as specified including a sheet 75 metal strip bent to form a pair of oppositely disposed channels adapted to springingly engage objects to be connected, the side edges of the strip forming the extremities of the inner channel walls being bent in- 80 wardly and back upon the walls to form a marginal enlargement to allow for expansion and contraction of the objects to be engaged and to reinforce the edges of said walls.

3. A device as specified including a pair of sheet metal sections, each section being formed of a single piece of sheet metal bent to form a pair of oppositely disposed channels, the center portion of each section connecting the outer edges of the channel walls and the bases of said opposed channels being spaced apart, and transverse connecting strips between said sections with their ends positioned between the spaced bases of the 90 channels and the extremities thereof bent laterally at their ends and disposed between the outer channel wall and adjacent the center portion of each section.

In testimony whereof, I affix my signature hereto.

RICHARD LEVENS.
